UNITED STATES PATENT OFFICE.

JESSE A. HARTWICK, OF CHICAGO, ILLINOIS.

HAND-HOLE SCRAPER.

1,282,691.

Specification of Letters Patent. Patented Oct. 22, 1918.

Application filed February 18, 1916. Serial No. 79,027.

To all whom it may concern:

Be it known that I, JESSE A. HARTWICK, a citizen of the United States of America, resident of Chicago, county of Cook, and 5 State of Illinois, have invented certain new and useful Improvements in Hand-Hole Scrapers, of which the following is a specification.

My invention relates to hand hole scrapers 10 of the kind in which cutting means are rotatably mounted so that the scraper is manipulated against the inner circumferential edge of a hand hole in the boiler sheet.

The cleaning of the inner circumferential 15 edge of the hand holes in a boiler sheet is difficult and originally was accomplished by the hand and chisel method. Scrapers as now commonly used for cleaning the hand hole edges are unsatisfactory because after

20 the scraper is in operative position a pull and a twisting motion must be applied to the handle to cause the blades of the scraper to engage the inner edge of the hand holes.

A further reason why this type has been 25 unsatisfactory is because an equal pull cannot be applied to all of the blades due to the pull and twist motions that must be applied to accomplish the cleaning of the edge of the hand hole thus bringing about an un-

30 even surface. The scraper of my invention overcomes this objection as I provide means which applies this pull automatically and equally on all the blades, therefore I am enabled to obtain a perfect bright and clean 35 surface which is very essential.

The invention further comprises the novel 40 details of construction, parts and combination of parts hereinafter described and particularly pointed out in the appended claims,

45 reference being had to the accompanying drawings forming a part thereof in which the same reference characters designate like parts throughout the several views and in which—

Figure 1 is an elevation of my hand hole 50 scraper showing it in operative position in the boiler sheet;

Fig. 2 is a plan view of Fig. 1 with parts 55 broken away showing ratchet and pawl arrangement in handle;

Fig. 3 is a bottom view of Fig. 1;

Fig. 4 is a sectional view of the hand hole 60 scraper showing the internal construction; and

Fig. 5 is a fragmentary view showing the

method of inserting the scraper in a hand hole of the boiler plate.

Referring now more in detail to my invention as illustrated and referring particularly to Figs. 1 to 5 inclusive, in which the 60 device of my invention is used as a hand hole scraper for cleaning the inner circumferential edges of the hand hole in the boiler sheet, the device comprises a tube shaped member 1, its lower extremity terminating 65 into an enlarged outwardly flanged portion 2. A portion of the flange 2 of the member 1 is turned down to a size to fit into a hand hole opening 4 in the boiler sheet 5. The under cut shoulder 6 thus formed by the 70 turned down portion 3 forms a bearing surface, which rests against the outer surface of the boiler sheet 5 when the device is placed in position to clean a hand hole, as shown most clearly in Fig. 1. The member 1 75 has a cylindrically shaped extension 7 preferably integral with the member 1 extending downwardly and having an opening 8 through which operating shaft 9 extends, the said opening 8 forming a bearing for the 80 shaft 9 when it is rotated. The shaft 9 extends up through the member 1 for purposes as will be more fully hereinafter described. The portion 10 of the shaft extending 85 beyond the cup-shaped extension 7 is flattened and inserted in an opening 11 formed by the two bars 12, which serves as a blade holder for the scraper blades. A helical coil spring 13 is placed around the shaft 9 in the tube-shaped member 1, one end of the said spring 90 resting in the cylindrically-shaped extension 7 of the member 1. The shaft 9 has a collar 16 fastened to it in any suitable manner as by means of the pin 17. In assembling the device, the spring 13 is placed around the 95 shaft 9, then the collar 16 is slipped over the shaft 9 and pinned to the said shaft by means of the pin 17 thus placing the spring 13 under tension. The upper portion 14 of the member 1 is threaded to receive a cap 15 100 in the form of a nut, the said cap 15 having screw threaded engagement with the threaded portion 14 of the member 1. The cap 15 serves as a cap for the member 1 and also serves as a bearing and a stop for the collar 16 when the spring 13 is placed under tension. A crank 19 is provided for rotating the shaft 9, the said crank being loosely 105 fastened to the shaft 9 in any suitable manner as by means of a nut 20. A hand grip 110

19¹ is fastened to the outer extremity 21 of the arm 19 in any suitable manner as by means of the nut 22. The device is adapted to be rotated in a clockwise direction when 5 cleaning hand holes, away from the edge of the boiler frame but when working on hand holes near the edge of the boiler frame where a full rotation of the handle is not possible, means is provided in the form of a well-known ratchet and pawl arrangement to 10 permit a partial turn of the crank.

The ratchet arrangement comprises a toothed wheel 23 which is suitably staked by means of a suitable pin to the shaft 9. 15 The wheel 23 sets in a recess 24 in the handle 19 in position to be engaged by a pawl 25 which is pivotally mounted in the recess 24 by means of the pivot pin 26. The pawl 25 is held in engagement with the ratchet 20 wheel 23 by means of a spring 27. A suitable cover plate 28 is pinned to the handle 19 and forms a covering for the recess containing the ratchet and pawl mechanism, and also forms a bearing surface for the 25 nut 20. The portion 9¹ of the shaft 9 extends slightly beyond the cover 28 forming a shoulder against which the nut 20 rests thus holding the handle 19 loosely upon the shaft 9. When the member 19 is rotated in 30 a clockwise direction pawl 25 is held in engagement with the ratchet 23. Now when only a limited movement of the handle is possible, the return movement of the handle is allowed in a counterclockwise direction. 35 without rotating the shaft 9, due to the pawl 25 riding over the teeth of the ratchet wheel 23, thus allowing a full rotation of the scraper S even though the handle 19 can be rotated only part way. The scraper 40 S as before mentioned, is constructed of two bars 12 to form a blade holder for the scraper blades 30 and 31, the said blades being held in the blade holder by means of bolts 36, 37 provided with nuts 38, 39. The 45 blade holder is pivotally attached to shaft 9 by means of a bolt 32 and nut 33.

To insert the attached scraper S into a hand hole 4 of the boiler sheet 5, a downward pressure is applied upon the handle 50 19 against the normal tension of the spring 13 and the scraper S is then tilted and inserted into the hand hole 4 as illustrated in Fig. 5, until the flanged portion 6 of the member 1 rests against the outer face of the 55 boiler plate and the annular portion 3 fits into the said hand hole. The pressure is then released from the handle 19 and the spring 13 tends to restore the shaft 9 to normal drawing the scraper blades 30, 31 60 of the scraper member S against the inner circumferential edge of the hand hole 4. The operating mechanism B is thus held in place in the hand hole 4 by the spring tension of coil spring 13. The turning 65 of the handle 19 in a clockwise direction

rotates the blades of the scraper S and their knife edges remove all foreign matter about the surface of the hand hole forming a true bearing surface about the said hand hole. It is thus seen that the spring 13 70 draws the scraper blades 30, 31 against the inner circumferential edge of the boiler sheet and that pressure, due to the spring 13 being under tension, is automatically applied and is equally distributed so that 75 the blades all engage the plate with the same amount of pressure. Now, only a rotary motion of the mechanism is necessary to clean the hand holes. It is thus seen that a great amount of labor is saved, 80 as well as a great amount of time in using the device of my invention over the prior devices that required both a pulling and a twisting motion, and the hand holes can be cleaned better and a truer surface obtained. To remove the scraper pressure is again applied to the handle 19, the scraper is then tilted as before and withdrawn from the hand hole. 85

While I have described my invention operating in connection with a certain form of opening, I do not wish to be limited to this exact disclosure and construction of parts as many changes and modifications may be made which will readily suggest themselves but I aim to cover all such changes and modifications which come within the spirit and scope of the appended 95 claims.

Having described my invention what I 100 claim as new and desire to secure by Letters Patent is:

1. A device of the character described including a cylindrical member having an enlarged outwardly flanged bottom portion, 105 an integrally formed cylindrical tube extending down into said flanged bottom portion, a shaft extending through said cylindrical tube, a collar secured to said shaft, a helical spring contained within said cylindrical member surrounding said shaft and having its one end bearing against the bottom portion of said cylindrical tube and its other end bearing against said collar, a plurality of cleaning members secured to said 110 shaft, a handle for rotating said shaft, and ratchet and pawl mechanism connecting said handle to said shaft.

2. A device of the character described including a cylindrical member having an enlarged outwardly flanged bottom portion, 115 an integrally formed cylindrical tube extending down into said flanged bottom portion, a shaft extending through said cylindrical tube, a collar secured to said shaft, a helical spring contained within said cylindrical member surrounding said shaft and having its one end bearing against the bottom portion of said cylindrical tube and its other end bearing against said collar, and 120

125

a plurality of cleaning blades connected to said shaft.

3. A device of the character described including a cylindrical member having an enlarged outwardly flanged bottom portion, an integrally formed cylindrical tube extending down into said flanged bottom portion, a shaft extending through said cylindrical tube, a collar secured to said shaft, a helical spring contained within said cylindrical member surrounding said shaft and having its one end bearing against the bottom portion of said cylindrical tube and its other end bearing against said collar, a blade carrying member pivotally secured to said shaft, a plurality of blades removably held by said blade carrying member, and means for rotating said shaft.

4. A device of the character described including a tubular supporting member provided with an integrally formed outwardly

flanged portion, a cylindrical orifice extending the length of said supporting member, a rotary shaft extending through said orifice, a helical spring contained within said orifice and surrounding said shaft having its one end bearing against one end of said supporting member and its other end bearing against a collar secured to said shaft, a member secured to said supporting member against which said collar bears, a plurality of cleaning blades secured to said shaft, and means for rotating said shaft to cause said blades to operate on said plate.

Signed by me at Chicago, county of Cook and State of Illinois in the presence of two witnesses.

JESSE A. HARTWICK.
